(57) **CLAIM**

The ornamental design for a linked hearts carabiner, as shown and described.

DESCRIPTION

FIG. 1 is a front elevation view of my new design for a linked hearts carabiner. The broken lines represent portions of the linked hearts carabiner that forms no part of the claim.

FIG. 2 is a back elevation view of FIG. 1.

FIG. 3 is a left side elevation view of FIG. 1.

FIG. 4 is a right side elevation view of FIG. 1.

FIG. 5 is a top plan view of FIG. 1.

FIG. 6 is a bottom plan view of FIG. 1.

FIG. 7 is a front perspective view of FIG. 1.

FIG. 8 is a front elevation view of a second embodiment of my new design for a linked hearts carabiner. The broken lines represent portions of the linked hearts carabiner that forms no part of the claim.

FIG. 9 is a back elevation view of FIG. 8.

FIG. 10 is a left side elevation view of FIG. 8.

FIG. 11 is a right side elevation view of FIG. 8.

FIG. 12 is a top plan view of FIG. 8.

FIG. 13 is a bottom plan view of FIG. 8.

FIG. 14 is a front perspective view of FIG. 8.

FIG. 15 is a front elevation view of a third embodiment of my new design for a linked hearts carabiner. The broken lines represent portions of the linked hearts carabiner that forms no part of the claim.

FIG. 16 is a back elevation view of FIG. 15.

FIG. 17 is a left side elevation view of FIG. 15.

FIG. 18 is a right side elevation view of FIG. 15.

FIG. 19 is a top plan view of FIG. 15.

FIG. 20 is a bottom plan view of FIG. 15.

FIG. 21 is a front perspective view of FIG. 15.

FIG. 22 is a front elevation view of a fourth embodiment of my new design for a linked hearts carabiner. The broken lines represent portions of the linked hearts carabiner that forms no part of the claim.

(Continued)

FIG. 23 is a back elevation view of FIG. 22.
 FIG. 24 is a left side elevation view of FIG. 22.
 FIG. 25 is a right side elevation view of FIG. 22.
 FIG. 26 is a top plan view of FIG. 22.
 FIG. 27 is a bottom plan view of FIG. 22.
 FIG. 28 is a front perspective view of FIG. 22.
 FIG. 29 is a front elevation view of an fifth embodiment of my new design for a linked hearts carabiner; the back elevation view being a mirror image thereof. The broken lines represent portions of the linked hearts carabiner that forms no part of the claim.
 FIG. 30 is a left side elevation view of FIG. 29.
 FIG. 31 is a right side elevation view of FIG. 29.
 FIG. 32 is a top plan view of FIG. 29.
 FIG. 33 is a bottom plan view of FIG. 29.
 FIG. 34 is a front perspective view of FIG. 29.
 FIG. 35 is a front elevation view of a sixth embodiment of my new design for a linked hearts carabiner; the back elevation view being a mirror image thereof. The broken lines represent portions of the linked hearts carabiner that forms no part of the claim.
 FIG. 36 is a left side elevation view of FIG. 35.
 FIG. 37 is a right side elevation view of FIG. 35.
 FIG. 38 is a top plan view of FIG. 35.
 FIG. 39 is a bottom plan view of FIG. 35.
 FIG. 40 is a front perspective view of FIG. 35.
 FIG. 41 is a front elevation view of a seventh embodiment of my new design for a linked hearts carabiner; the back elevation view being a mirror image thereof. The broken lines represent portions of the linked hearts carabiner that forms no part of the claim.
 FIG. 42 is a left side elevation view of FIG. 41.
 FIG. 43 is a right side elevation view of FIG. 41.
 FIG. 44 is a top plan view of FIG. 41.
 FIG. 45 is a bottom plan view of FIG. 41.
 FIG. 46 is a front perspective view of FIG. 41.
 FIG. 47 is a front elevation view of an eighth embodiment of my new design for a linked hearts carabiner; the back elevation view being a mirror image thereof. The broken lines represent portions of the linked hearts carabiner that forms no part of the claim.
 FIG. 48 is a left side elevation view of FIG. 47.
 FIG. 49 is a right side elevation view of FIG. 47.
 FIG. 50 is a top plan view of FIG. 47.
 FIG. 51 is a bottom plan view of FIG. 47; and,
 FIG. 52 is a front perspective view of FIG. 47.
